ATTORNEYS

UNITED STATES PATENT OFFICE.

ALBERT C. BARLEY, OF STREATOR, ILLINOIS.

DESIGN FOR AN AUTOMOBILE-BODY.

49,719.

Specification for Design.

Patented Oct. 3, 1916.

Application filed July 5, 1916. Serial No. 107,708. Term of patent 7 years.

To all whom it may concern:

Be it known that I, ALBERT C. BARLEY, a citizen of the United States, residing at Streator, in the county of La Salle and State of Illinois, have invented a new, original, and ornamental Design for Automobile-Bodies, of which the following is a specification, reference being had to the accompanying drawing, forming part thereof.

Figure 1 is a plan view and Fig. 2 a side elevation of an automobile body, showing my new design.

I claim:

The ornamental design for an automobile body, as shown.

ALBERT C. BARLEY.
